UNITED STATES PATENT OFFICE.

DAVID C. BARNARD AND EDWARD L. WALLACE, OF LOCKPORT, NEW YORK.

WASHING-MACHINE.

SPECIFICATION forming part of Letters Patent No. 371,730, dated October 18, 1887.

Application filed April 16, 1887. Serial No. 235,112. (M. del.)

To all whom it may concern:

Be it known that we, DAVID C. BARNARD and EDWARD L. WALLACE, of Lockport, in the county of Niagara and State of New York, 5 have invented a new and useful Improvement in Washing-Machines, of which the following is a specification.

This invention is an improvement in washing-machines; and it consists in certain novel 10 constructions and combinations of parts, which will be hereinafter more fully described, and particularly pointed out in the claim.

In the drawings, Figure 1 is a side elevation of the machine as when not in use, parts being 15 broken away to show the location of the roller-frame. Fig. 2 is a vertical longitudinal section of the machine as in use, and Fig. 3 is a detail view.

The suds-box A is supported at one end on 20 legs B, and has at its opposite end short legs c, to which are journaled wheels C, on which the machine may be conveniently moved by the user or may be wheeled by a canvasser in selling the machines. Bars D extend between 25 and connect the legs B with legs c below the suds-box A. Spring-bars E are secured at one end to the bars D and are separated at their other ends from said bars by means of interposed blocks d. To the free ends of these 30 spring-arms are pivoted the lower ends of arms F, to the upper ends of which are connected the rear ends of the rubber-frame G, which has the handle g at its opposite end, and is provided between its ends with the rubber H.

The bed or roller frame I consists of sides i, the rods J, connecting the same, and the rollers K, journaled between the sides i, as shown.

The suds-box is divided by two transverse partitions, L L', into three compartments, which, for convenience of reference, we shall refer to as the "central" compartment, l, the "front" compartment, l', and the "rear" compartment, l''. The partition L' is usually made higher than 40 the partition L, so the front compartment will hold the most water; also in order to support the bed or roller frame at the desired angle. It is usual to provide the central compartment with the discharge-opening l', a suitable plug 45 being provided to close said opening when desired.

In operation the compartments l' l'' contain the water for washing the clothes, while the dirty water is pressed out of the clothes by the action of the rubber and rollers, and passes 55 into the middle compartment and out thereof through the discharge-opening, the water in the end compartments remaining comparatively clean. By elevating the rollers (which should not be submerged) on the partitions we 60 secure a depth of the end compartments sufficient to properly wet the clothes at once, the clothes being alternately soaked in compartments l' or l'', and then pressed or rubbed in compartment l, being soaked meanwhile, as 65 will be understood. Thus the partitions, in addition to forming the box into compartments, serve to elevate the rollers and support them properly over the compartment l, whereas if the rollers were placed upon the 70 bottom of the suds-box without compartments there could be had but little depth of water in the machine, as the rollers must not be submerged, and there would be no separation of the clean water from the dirty. Boiling 75 water can be used, as the hands need not be put therein. After the rubbing has been completed, the roller-frame may be removed and the several compartments be used--the one for sudsing the clothes, another for rinsing, and 80 third for bluing the same, thus dispensing with an extra tub. When not in use, the several parts may be adjusted to the position shown in Fig. 1 and the cover M be applied, when the machine will form a convenient 85 table for ironing or other purposes.

By placing the partitions in the bottom of the suds-box the bottom of said box is braced and strengthened.

Manifestly the partitions may be made of 90 any suitable height. It is preferred to provide a discharge-opening through the bottoms of each of the compartments, as shown.

It will be noticed that we provide end compartments and a central or intermediate compartment in the suds-box, which are separated by partitions, and support the bed over 95 said intermediate compartment, the end compartments being in practice supplied with water. Now, in use, it will be seen, the clothes 100 may extend over the bed and rest at each end in the water in the end compartments, thus

insuring the thorough wetting of the clothing as the operation proceeds. It will be further seen that by the aid of the rubber the clothing may be manipulated as desired without being touched by the hand, and that all the dirt will be pressed out of the clothing and pass through the bed into the central or intermediate compartment, where it will be kept from contact with the clothing. Manifestly, by keeping the clothing being washed from contamination by the dirt previously washed out, the washing is greatly expedited and can be more thoroughly effected with less labor than if the dirt mingled with the clothes during the entire operation; also, by having the bed and the dirt-receiving compartment between two water-compartments the clothing may be immersed at both ends in the water while its central portion is being washed, so that the clothing, with the exception of that part being immediately treated by the rubber, will be soaking and getting in proper condition for such treatment.

Having thus described our invention, what we claim as new, and desire to secure by Letters Patent, is—

The improved washing-machine herein described, consisting of the suds-box, the cross-boards or partitions L L', dividing such suds-box into end compartments, and an intermediate compartment located between said end compartments and formed between the partitions or cross-boards L L', the bed-frame consisting of the sides i, fitting between the partitions L L', brace-rods J, extended between the sides i, the rollers journaled in said sides, and the rubber, all substantially as and for the purposes specified.

DAVID C. BARNARD.
EDWARD L. WALLACE.
